UNITED STATES PATENT OFFICE.

FRANK F. SLOCOMB, OF PHILADELPHIA, PENNSYLVANIA, ASSIGNOR TO F. F. SLOCOMB & CO., INCORPORATED, A CORPORATION OF DELAWARE.

LEATHER-STAKING MACHINE.

1,130,769.

Specification of Letters Patent. Patented Mar. 9, 1915.

Original application filed November 6, 1911, Serial No. 658,646. Divided and this application filed June 26, 1914. Serial No. 847,398.

To all whom it may concern:

Be it known that I, FRANK F. SLOCOMB, a citizen of the United States, residing in the city and county of Philadelphia, State of Pennsylvania, have invented a new and useful Leather-Staking Machine, of which the following is a specification.

My present invention consists of a novel construction of a leather staking machine wherein the rollers which coact with the cams on the connecting rod are mounted in a novel manner in order that said rollers will at all times coöperate with the operative surface of the cam.

It further consists of a novel construction of a leather staking machine wherein novel means are provided for limiting the upward movement of the jaws in order to prevent injury to the operator.

It further consists of other novel features of construction, all as will be hereinafter fully set forth.

This application is a division of an application for Letters Patent for leather staking machine, Serial No. 658,646, filed by me on November 6, 1911.

For the purpose of illustrating my invention, I have shown in the accompanying drawings, one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a sectional elevation of a leather staking machine embodying my invention, a portion of the same being broken away. Fig. 2 represents a front elevation of a portion of Fig. 1. Fig. 3 repre-

sents a sectional elevation of another embodiment of my invention. Fig. 4 represents a side elevation of a portion of Fig. 1, the roller and its adjuncts being omitted. Fig. 5 represents a sectional elevation of

Fig. 4.

Similar numerals of reference indicate corresponding parts in the figures.

Referring to the drawings—1 designates the housing of the machine which may be of any desired construction.

55

2 designates a connecting rod, a portion of the same being broken away, it being of course understood that said connecting rod may be actuated or reciprocated by means of a crank or other device (not shown). 3 60 designates a pin or pivot common to said connecting rod and the plates 4, the general contour of said plates being understood by reference to Fig. 1, said plates when in position forming with their adjuncts, a 65 cross head 5 which reciprocates in suitable slides, and a detailed description of the latter is unnecessary since the same is old in the art.

Pivoted at 6 to the plates 4 is an upper 70 jaw 7, and pivoted at 8 to the plates 4 is the lower jaw 9. The upper jaw 7 has secured thereto in the usual manner, a bracket 10 through which passes a threaded stem 11, which is secured with respect to the bracket 75 by means of suitable nuts 12 and 13. The lower end of the threaded stem 11 is forked, as indicated at 14, in order to receive the journal 15 which is pivoted with respect thereto by means of bolts and nuts 16, or 80 equivalent fastening devices.

17 designates a roller carried by the forked end of the journal 15 and secured therein by means of a bearing pin 18, said roller coöperating with the cam 19 on the connecting rod 2, as will be apparent by reference to Fig. 1.

20 designates rods which are mounted on the pivot pin 3 and extend through a cross bar 21, carried by the bracket 10, and 90 at their upper end they are provided with a plurality of nuts 22 having threaded engagement therewith and one of which serves as a lock nut.

23 is a washer between which and the 95 cross bar 21 is interposed a spring 24, it being understood by reference to Fig. 5 that two of these rods 20 and their adjuncts are employed.

In order to positively limit the extent of 100

downward movement of the bracket 10, it is desirable in some cases to provide a stop therefor, and in Fig. 3, I have shown one type of a construction which will accomplish this result. The rod 20 is provided with a shoulder or a top 25 integral therewith or adjustable thereon, so that when the upper jaw 7 rocks on its pivot 6 the downward movement of the bracket 10 will be limited. This limiting of the downward movement of the bracket 10, and thereby the upward movement of the forward end of the upper jaw 7 which carries the rollers may also be obtained by providing a strap 26 which passes over the jaw 7 on the opposite side of the pivotal pin 6 thereof, and is secured to the plates 4 of the cross head 5 by means of fastening devices 27, as will be best understood by reference to Figs. 1, 4 and 5. The forward ends of the jaws carry staking rollers 63 and 64, and blades, 65 and 66, between which the skin is placed and operated upon.

57 is a spring suitably secured to the housing and having one end bearing against the lower jaw 9, whereby the roller 58 will engage with the cam 59 on the connecting rod 2. The roller 58 is mounted in a similar manner to the roller 17, seen in the upper portion of Fig. 1, and a detailed description of such mounting is therefore unnecessary.

64 designates the front roller which is adjustably mounted with respect to the upper jaw 7 in the usual manner, and a detailed description is therefore unnecessary.

61 is a skin to be treated and 62 is a breast roller which is supported in bearings in the forward part of the machine in any desired manner.

The operation will now be readily apparent to those skilled in this art, and is as follows:—The jaws 7 and 9 when at or near their extreme forward position appear as seen in Fig. 1, the staking blade 66 assuming a position intermediate the rollers 63 and 64. The hide to be staked is placed in position and held between the body of the operator and the breast roller 62, and the rollers 63 and 64, and the blades 65 and 66 are caused to move rearwardly through the medium of the connecting rod 2, and since the hide is held stationary by the operator, it will be apparent that the proper treatment will be imparted thereto during the rearward movement of the rollers 63 and 64, and the blades 65 and 66, the operator or attendant shifting the hide or skin until every portion of the same has been properly treated or staked.

Special attention is directed to certain of the novel features of my present invention. In devices of this character as heretofore constructed, considerable difficulty has arisen

owing to the wear of the rollers 17 and 58 with respect to the cams 19 and 59, and since these rollers are ordinarily mounted in stationary bearings, the proper provision has not been made for causing the rollers to properly coöperate with the cam. In my present device it will be seen that the roller 17 is pivotally carried by the threaded stem 11 so that the same may oscillate and accommodate itself to the operative face of the cam 19, so that the roller 17 will at all times engage the operative face of the cam 19 instead of only a portion thereof.

In devices of this character as heretofore constructed, there is a likelihood of the upper jaw bounding upwardly, and since the operator is bending thereover in order to properly manipulate the hide 61, it sometimes happens that the attachment secured to the upper jaw 7 will strike the operator, and in order to positively prevent this, I provide means for limiting the upward movement of the forward end of the jaw 7 which may be accomplished by placing a stop on the rods 20, as seen in Fig. 3, or another manner in which this can be advantageously accomplished is by providing the strap 26 which will limit the upward movement of the forward end of the jaw 7 as is apparent.

It will now be apparent that I have devised a novel and useful construction of a leather staking machine which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a leather staking machine, an upper jaw, means for reciprocating and rocking the same, and means independent of said rocking and reciprocating means for limiting the upward rocking movement of the forward end of the upper jaw.
2. In a leather staking machine, an upper jaw, means for reciprocating and rocking the same, and a fixed stop separate from said means limiting the upward rocking movement of the forward end of the upper jaw.
3. In a leather staking machine, upper and lower jaws, journal-supports pivoted to laterally oscillate upon the same, rollers journaled in such supports, cams bearing against said rollers to open and close said jaws,

and means for rocking and reciprocating said cams.

4. In a leather staking machine, upper and lower jaws, brackets carried thereby, 5 threaded stems carried by said brackets, rollers pivotally carried by said stems to have laterally oscillatory movement, cams

bearing against said rollers to actuate said jaws, and means for rocking said cams.

FRANK F. SLOCOMB.
